CLAIM

I claim the ornamental design for an electrically operated actuator, as shown and described.

DESCRIPTION

FIG. 1 is a front view according to a first embodiment of the present design;

FIG. 2 is a back view of the first embodiment;

FIG. 3 is a plan view of the first embodiment;

FIG. 4 is a bottom view of the first embodiment;

FIG. 5 is a right side view of the first embodiment;

FIG. 6 is a left side view of the first embodiment;

FIG. 7 is a reference perspective view as viewed from the front direction according to the first embodiment;

FIG. 8 is a perspective view from the back of the first embodiment, in a retracted position;

FIG. 9 is a perspective view from the back of the first embodiment, in a protracted position;

FIG. 10 is a front view of the second embodiment of the present design;

FIG. 11 is a back view of the second embodiment;

FIG. 12 is a plan view of the second embodiment;

FIG. 13 is a bottom view of the second embodiment;

FIG. 14 is a right side view of the second embodiment;

FIG. 15 is a left side view of the second embodiment;

FIG. 16 is a reference perspective view as viewed from the front direction according to the second embodiment;

FIG. 17 is a perspective view from the back of the second embodiment, in a retracted position; and,

FIG. 18 is a perspective view from the back of the second embodiment, in a protracted position.

The broken lines show portions of an electrically operated actuator that form no part of the claimed design.

1 Claim, 18 Drawing Sheets
